UNITED STATES PATENT OFFICE.

WILLIAM H. FELDING, OF PITTSBURGH, PENNSYLVANIA, ASSIGNOR TO NATIONAL TUBE COMPANY, A CORPORATION OF NEW JERSEY.

UPSETTING DEVICE.

Application filed March 11, 1926. Serial No. 94,024.

This invention relates to upsetting devices and more particularly to upsetting devices particularly adapted for upsetting the ends of tubular articles, such as pipe, and has for its object the provision of a novel combination of apparatus for upsetting the ends of pipe, whereby the pipe is held intermediate its ends during the upsetting operation, so that random length pipes may be upset without any adjustment of the apparatus.

Another object is to provide a novel form of frictional gripping device which will hold the pipe against longitudinal movement during the upsetting operation, and which will permit the pipe to slip to take up the excess stroke of the upsetting or forging apparatus.

A further object is to provide a novel form of upsetting device for upsetting the ends of tubular articles, such as pipe, having the novel construction, design and combination of parts hereinafter described and illustrated in the accompanying drawings.

In the drawings:

Figure 1 is a plan view of the upsetting apparatus.

Figure 2 is a side elevation thereof.

Figure 3 is an enlarged plan of the gripping apparatus.

Figure 4 is an enlarged detail plan of the gripping device with parts removed and part in section.

Figure 5 is an end elevation.

Figure 6 is a sectional end elevation on the line VI—VI of Figure 4.

Referring more particularly to the drawings, the letter A designates a heating furnace for heating the ends of the pipe B to be upset, which pipe are supported on bed rails C. The pipe B are adapted to be rolled from the bed C onto a jack-stand D and to be upset by a forging machine E of standard design, which is provided with two pairs of co-acting matrix and patrinx upsetting dies 2 and 3, and 4 and 5 respectively, the pairs of dies being spaced vertically.

The jack-stand D is of standard and well-known construction and is provided with jack-rollers 6 and 7 adapted to support the pipe to be upset, and to be raised and lowered by a fluid pressure cylinder 8 to position the pipe in the proper plane to be acted upon by the pairs of dies 2, 3 and 4, 5.

The apparatus so far described is well-

known and commonly used in the art and will not be further described in detail.

Heretofore a back-stop has been employed at the end of the jack-stand to back up the pipe being upset and prevent endwise movement of the pipe during the upsetting operation. When a back-stop is used the pipe must all be of exactly the same length, or else the back-stop must be adjusted for all the different length of pipe, this operation requiring the use of an extra operator, and causing delay in the upsetting operation until the back-stop was adjusted.

The present invention eliminates the use of a back-stop and provides means for holding the pipe intermediate its ends, so that any length pipe may be upset, and the use of an extra operator is eliminated since the novel pipe holding apparatus of this invention is readily operable by the forging or upsetting machine operator.

This invention provides a pipe gripping or holding apparatus designated as a whole by the letter F, and comprising a housing 9 fixed to a base 10 by bolts 11, and provided with a window or opening 12 in which the moving parts are mounted.

A pair of bottom wedge-plates 13 and 14 are secured on the bottom wall of the window 12 and are provided with wedge-tongues 15.

A pair of wedge-blocks 16 and 17 are mounted on the plates 13 and 14, respectively, and provided with wedge-grooves 18 adapted to receive the tongues 15. A second pair of wedge-plates 19 and 20 are secured to the upper ends of the side walls of the housing 9 and extend over the window 12. The plates 19 and 20 are each provided with wedge-tongues 21 adapted to fit in wedge-grooves 22 in the top faces of the wedge-blocks 16 and 17.

When the blocks 16 and 17 are reciprocated longitudinally relative to the wedge-plates 13, 14 and 19, 20, the grooves 18 and 22 in the blocks will cooperate with the tongues 15 and 21 respectively, to force the blocks to move toward or away from each other according to the direction of reciprocation of the blocks.

The wedge-blocks 16 and 17 are provided with die-blocks or article engaging jaws 24 and 25 respectively, on their inner faces which are secured to the blocks by bolts 26.

The jaws 24 and 25 are each provided with a pair of vertically spaced grooves 27 and 28 adapted to aline with the pipe to be upset in its upper and lower positions, respectively. The grooves 27 and 28 are of less depth than half the diameter of the pipe, so that the jaws may be moved toward each other sufficiently to tightly grip the pipe in the jaws 24 and 25.

10 The wedge-blocks 16 and 17 are adapted to be reciprocated by a fluid pressure cylinder 29 through a suitable link and lever mechanism to be described.

A shaft 30 is journaled in suitable bearings 15 31 on the rear of the housing 9 and carries levers 32 and 33 which are connected by a series of links 34, 35, 36 and 37, 38 and 39 respectively, to pivot pins 40 and 41 mounted in the respective blocks 16 and 17.

20 The shaft 30 is provided with a rocking lever 42 which is connected by a link 43 with the piston rod 44 of the cylinder 29.

In operation, the pipe B is moved onto the jack-stand D and the jack-rollers 6 and 7 25 are lowered to move the pipe into position for upsetting by the dies 2 and 3. The cylinder 29 is then actuated to rock the shaft 30 and thereby move the wedge-blocks 16 and 17 forwardly which, due to the co-acting 30 tongues 18 and 22 and grooves 15 and 21, will be forced toward each other to grip the pipe in the grooves 27 in jaws 24 and 25. The grip of the jaws 24 and 25 will be sufficient to hold the pipe against endwise movement during the upsetting operation, but 35 will permit the pipe to slip if the upsetting or forging stroke is excessive.

After the end of the pipe B has thus been upset, the cylinder 29 is operated to release 40 the jaws 24 and 25 and the jack-rollers 6 and 7 are raised to elevate the pipe into position for the second upsetting and rounding-up operation by the dies 4 and 5. The cylinder is again operated to close the jaws 24 45 and 25 and grip the pipe in the grooves 28 so as to hold the pipe against endwise movement during this second upsetting and rounding-up operation.

After the second upsetting and rounding-up operation is completed the jaws 24 and 25 50 are again released and the pipe removed.

It will be readily appreciated that I have provided an upsetting apparatus capable of upsetting random length pipes without 55 change or adjustment and, therefore, the

employment of an operator for manipulating the back-stop ordinarily used is dispensed with.

While I have shown and described one specific embodiment of my invention it will be understood that I do not wish to be limited thereto since various modifications may be made without departing from the scope of my invention as defined in the appended claims.

I claim:

1. In an apparatus for upsetting tubular articles, a housing having a window therein, a pair of wedge-plates secured on the bottom wall of said window, upstanding wedge-tongues on said plates, a pair of wedge-blocks mounted on said wedge-plates and provided with wedge-grooves to receive said wedge-tongues, a second pair of wedge-plates secured to said housing and overlying said wedge-blocks, said last named plates being provided with downwardly extending wedge-tongues adapted to be engaged in wedge-slots in said wedge-blocks, article engaging jaws secured to the inner faces of said wedge-blocks, and power means for reciprocating said wedge-blocks relative to said wedge-plates to move said article engaging jaws toward and away from each other so as to grip and release the articles to be upset.

2. In an apparatus for upsetting tubular articles, a housing having a window therein, a pair of wedge-plates secured on the bottom wall of said window, upstanding wedge-tongues on said plates, a pair of wedge-blocks mounted on said wedge-plates and provided with wedge-grooves to receive said wedge-tongues, a second pair of wedge-plates secured to said housing and overlying said wedge-blocks, said last named plates being provided with downwardly extending wedge-tongues adapted to be engaged in wedge-slots in said wedge-blocks, article engaging jaws secured to the inner faces of said wedge-blocks, a link and lever mechanism connected to said wedge-blocks, and a fluid pressure cylinder for actuating said link and lever mechanism to reciprocate said wedge-blocks relative to said wedge-plates and thereby move said article engaging jaws toward and away from each other so as to grip and release the articles to be upset.

In testimony whereof, I have hereunto signed my name.

WILLIAM H. FELDING.
